WINDOW CONSTRUCTION

John M. Meck, New York, N. Y.

Application May 18, 1937, Serial No. 143,255

10 Claims.

(Cl. 20—42)

This invention relates to new and useful improvements in a window construction.

More specifically, the invention is characterized by the provision of a window frame having a sash frame removably mounted therein and being provided with several partitions dividing off areas for pane members, and each of the areas having slotted members on opposite sides thereof and the pane members being provided with slotted members on the opposite sides thereof and into which pivotal elements are slidably mounted for slidably and pivotally supporting the pane members in the sash frame.

As a further object of the invention it is contemplated to provide strips along the outer edge portion of the window frame against which the outer edge of the sash frame is adapted to abut to prevent the sash frame from slipping out of the window frame.

As a further object of the invention it is proposed to provide locking members on the inner edge of the sash frame which are adapted to engage openings in the window frame for locking the sash frame in position in the window frame with the front edge thereof abutting the strips.

Still further the invention provides a means for holding each of the pivotal elements in releasably fixed positions in the slotted members for pivotally supporting the pane members in selected slided positions.

As a further object of the invention it is proposed to provide each of the pivotal elements with a head portion which slidably engages over a shank portion and which are adapted to engage recesses in the opposite faces of the pane members and the partitions.

Still further the invention provides for resilient elements acting between the head portions and the slotted members for urging the head portions into the recesses.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is an inside elevational view of a window constructed according to this invention.

Fig. 2 is a rear elevational view of Fig. 1.

Fig. 3 is an enlarged detailed view taken on the line 3—3 of Fig. 1.

Fig. 4 is an enlarged detailed view taken on the line 4—4 of Fig. 2.

Fig. 5 is a view taken on the line 5—5 of Fig. 1.

Fig. 6 is a view taken on the line 6—6 of Fig. 1.

Fig. 7 is a view taken on the line 7—7 of Fig. 1.

Fig. 8 is a view taken on the line 8—8 of Fig. 1.

Fig. 9 is an enlarged perspective view taken on the line 9—9 of Fig. 1.

Fig. 10 is a perspective view of one of the pane members.

Fig. 11 is an enlarged detailed view of a portion of Fig. 3.

Fig. 12 is a sectional view taken on the line 12—12 of Fig. 11.

The window construction, according to this invention, comprises a window frame 10 having a sash frame 11 removably mounted therein and having several partitions 11a dividing off areas for pane members 12. Each of the areas have slotted members 13 on opposite sides thereof and the pane members 12 have slotted members 14 on opposite sides and are adapted to be located longitudinally adjacent the slotted members 13 when the pane member 12 is in the closed position. Pivotal members 15 are slidably mounted in the slotted members of the pane member 12 and pivotally and slidably engage the slotted members 13 for slidably and pivotally supporting the pane member 12 within the area.

The window frame 10 is of conventional construction and is provided along its outer edge with a strip 10a against which the outer edge of the sash frame 11 is adapted to engage to prevent the sash frame from sliding out through the front of the window frame 10. The inside edges of the partitions 11a mounted in the sash frame 11 are provided with a plurality of bearings 16. A rod 17 slidably engages through the bearings 16 and is adapted to engage an opening 18 in the window frame 10 to lock the sash frame 11 in position within the window frame 10 with the front edge thereof abutting the strips 10a. One of the ends 17a of the rod 17 is at right angles to the body portion of this rod and is for the purpose of facilitating the manual movement of this rod from its operative to inoperative positions, and vice versa.

Each of the slotted members on the opposite sides of the areas formed by the partitions 11a consist of a central portion 13a provided with a slot 19 and continuing into side portions 13b which in turn continue into face portions 13c which are adapted to abut the edges of the area forming hollow portions between the sides of the partition and the sides of the intermediate portion 13a.

Each of the slotted members on the opposite sides of the pane members 12 consists of an intermediate portion 14a having a slot 20 and which in turn continues into end portions at right angles to the intermediate portion and which engage the front and rear faces of the pane member for slidably holding the slotted members 14 in position thereon.

Each of the pane members may be of a different construction and any number may be pro-

vided within any single sash frame. The top pane member 12 is provided with glass 21 and the intermediate pane member 12 is provided with a screen 22 and a louvered member 23 (see Fig. 4). The bottom pane member is provided with a screen 22. This change of construction is merely for the purpose of illustrating that a variety of construction is possible within the scope of this invention and that I do not wish to be limited to any specific construction. The pane member 12 with either pane glass 21, screen 22, louvered member 23 or with any other air circulating arrangement may be used on windows of buildings, on doors, transoms, etc., and may be placed in position and interchanged according to this invention.

Each of the pivotal elements 15 consists of a shank portion 15^a which engages through the slots 19 and 20 in the slotted members 13 and 14. A head portion 15^b is slidably engaged over one of the ends of the shank member 15^a and engages recesses 25 in the partitions 11^a. The adjacent face of the pane member 12 is provided with a longitudinal groove 26 having recesses 27 in the lowermost portion thereof into which the head member 15^b on the other end of the shank member 15^a is adapted to engage in order to pivotally support the pane member 12 in selected slided positions within the said areas. The ends 30 of the shank member 15^a are provided with flange portions 15^{aa} which are adapted to abut inwardly directed flange portions 15^{bb} on the head portions 15^b to prevent complete disengagement of the head members from the shank members 15^a. A resilient washer 28 acts between the slotted members 13 and 14 and the head members 15^b for resiliently engaging these head members 15^b into the slots 25 and 27.

Each of the slotted members 14 on the pane members 12 are slidably engaged thereon and clamp screws 29 threadedly engage through openings 30 in the edge portions 14^b of the slotted members 14 and are adapted to abut the sides of the pane members 12 for fixedly holding the slotted members 14 in position thereon. A knob 31 is provided on the inner face of the pane member 12 in order to facilitate the movement of same within the areas formed by the partitions 11^a.

50 The operation of the device is as follows:

When it is desired to remove the sash frame 11 from the window frame 10, it is merely necessary to grasp the end 17^a of the member 17 and withdraw the other end of this member from the opening 18 in the frame 10 and move the sash frame forward to disengage it from the frame 10. To replace this sash frame 11 it is merely necessary to again replace the frame 11 within the frame 10 and then move the member 17 back to 60 its original position.

When it is desired to open the pane members 12, it is done by grasping knob 31 of the pane member 12 and then drawing the pane member 12 to any of the desired positions shown by the dot and dash line 12' in Fig. 8. The pivotal members 15 which connect together the slotted members 13 and 14 permit a movement of the pane members 12 within the sash frame 11. Thus, it is possible to draw the pane members inward and outward and across the sash frame 11 with relation to the slotted members 13. If for some reason it is desired to remove the pane members from the slotted members 14 it is done 75 by unloosening the clamp screws 29 and sliding

the pane member 12 out of the slotted members 14.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member.

2. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, means for locking said sash frame within said window frame.

3. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, means for locking said sash frame within said window frame, comprising strips along the outer edge of said window frame against which the outer edge of said sash frame is adapted to abut, and locking members for locking said sash frame in position within said window frame with said front edge abutting said strips.

4. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, means for locking said sash frame within

said window frame, comprising strips along the outer edge of said window frame against which the outer edge of said sash frame is adapted to abut, and locking members for locking said sash frame in position within said window frame with said front edge abutting said strips, said locking means comprising bearings mounted along the inner edge of said partitions and a rod slidably engaging said bearings and being adapted to have one of its ends engaging an opening in said window frame for locking said sash frame in a fixed position.

5. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, each of said slotted members engaging said pane members consisting of a strip of material having an intermediate portion and continuing into edge portions at right angles thereto and abutting the adjacent face of said pane member.

6. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, each of said slotted members engaging said pane members consisting of a strip of material having an intermediate portion and continuing into edge portions at right angles thereto and abutting the adjacent face of said pane member, said slotted member slidably engaging said pane member and clamp screws threadedly engaging through openings in said edge portions and being adapted to abut said pane member for holding said slotted members in position on said pane member.

7. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, and means for holding said pivotal elements in releasably fixed positions in said slotted members for pivotally supporting said pane member in selected slided positions.

8. A window construction comprising a window frame, a sash frame removably mounted in said frame and having several partitions dividing off

areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, and means for holding said pivotal elements in releasably fixed positions in said slotted members for pivotally supporting said pane member in selected slided positions, said means comprising shank members engaging through slots formed in the adjacent faces of said slotted members, head portions engaging over the ends of said shank members and being adapted to engage recesses in said pane members and said partitions.

9. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, and means for holding said pivotal elements in releasably fixed positions in said slotted members for pivotally supporting said pane member in selected slided positions, said means comprising shank members engaging through slots formed in the adjacent faces of said slotted members, head portions engaging over the ends of said shank members and being adapted to engage recesses in said pane members and said partitions, resilient means between said slotted members and said head portions for urging said head portions into said recesses.

10. A window construction comprising a window frame, a sash frame removably mounted in said frame and having several partitions dividing off areas for pane members, each of said areas having slotted members on opposite sides, a pane member having slotted members on opposite sides adapted to be located longitudinally adjacent said slotted members of said area when said pane member is in a closed position in said area, and pivotal elements slidably mounted in the slotted members of said pane members and pivotally and slidably engaging the slotted members of said area for slidably and pivotally supporting said pane member, and means for holding said pivotal elements in releasably fixed positions in said slotted members for pivotally supporting said pane member in selected slided positions, said means comprising shank members engaging through slots formed in the adjacent faces of said slotted members, head portions engaging over the ends of said shank members and being adapted to engage recesses in said pane members and said partitions, resilient means between said slotted members and said head portions for urging said head portions into said recesses, said resilient means comprising resilient washers coaxially engaging said shank members for forcing said head portions into said recesses.
